[57] CLAIM

The ornamental design for a wall lamp support, as shown and described.

DESCRIPTION

FIG. 1 is a perspective view of a wall lamp support showing my new design having two shades;

FIG. 2 is a left side elevational view of the wall lamp support, the right side being a mirror image;

FIG. 3 is a top plan view of the wall lamp support;

FIG. 4 is a bottom plan view of the wall lamp support;

FIG. 5 is a front elevational view of the wall lamp support;

FIG. 6 is a rear elevational view of the wall lamp support;

FIG. 7 is a perspective view of a second embodiment of my new design having three shades;

FIG. 8 is a left side elevational view of the wall lamp support, the right side being a mirror image;

FIG. 9 is a bottom plan view of the wall lamp support;

FIG. 10 is a top plan view of the wall lamp support;

FIG. 11 is a front elevational view of the wall lamp support;

FIG. 12 is a rear elevational view of the wall lamp support;

FIG. 13 is a perspective view of a third embodiment of my new design having five shades;

FIG. 14 is a left side elevational view of the wall lamp support, the right side being a mirror image;

FIG. 15 is a bottom plan view of the wall lamp support;

FIG. 16 is a top plan view of the wall lamp support;

FIG. 17 is a front elevational view of the wall lamp support;

FIG. 18 is a rear elevational view of the wall lamp support.
